ABSTRACT: The deformable electrical connector is made in part of a material which has the property which permits outwardly directed deformation of the connector without failure of the connector while also maintaining the structural stability of the connector during deformation. The connector comprises a sleeve made of deformable material and surrounded by an outer shell of higher tensile strength. The electrical connection is formed by pushing the connector onto a lead and post so that the lead initially penetrates the deformable sleeve of the connector and then, when the deformable sleeve develops the strength of the lead, flattens so as to completely fill the space between the connector and post.

RADIALLY DEFORMABLE ELECTRICAL CONNECTOR INCLUDING TWO CONTIGUOUS MEMBERS

This invention relates to a self-crimping connector and a method of making the same. More particularly, this invention relates to a self-crimping electrical connector and a method of making the same. Still more particularly, this invention relates to an electrical and mechanical connection utilizing a self-crimping connector.

Heretofore, electrical connectors have been made of various shapes, materials and sizes for electrically connecting electrical conductors together. In some instances, such connectors have frequently been shaped to receive and position the conductors for subsequent soldering or brazing techniques whereby a soldered or brazed joint is made between the connector and each conductor. In other instances, connectors have been made of deformable material and shaped so as to be crimped or otherwise cold-worked onto a conductor to form a solderless connection.

However, these cold workable connectors have frequently not been as reliable as other electrical connectors since the connections made therewith have not always been gastight. In those instances where a gas has been trapped within the connection, the gap occupied by such has caused higher resistances to exist in the connections. In addition, where the gas has been an oxidizing gas, the metals of the connection have become oxidized and as such have created higher resistances. While the higher resistances have been of small value, in certain installations the increase in resistance values have been relatively great, for example, in computer circuits. Consequently, it has frequently been necessary to exercise extreme care in forming connections with these connectors. Further, where there has been limited space for making electrical connections, these connectors have frequently not been used since the tools necessary for making the connections have not had sufficient room to operate properly.

Accordingly, it is an object of the invention to provide a self-crimping electrical connector.

It is another object of the invention to provide a self-crimping connection for a limited working space.

It is another object of the invention to provide a connector capable of forming a gastight electrical connection.

It is another object of the invention to provide a method of making a self-crimping connector.

It is another object of the invention to provide a method of making a gastight connection between electrical conductors with a self-crimping connector.

Briefly, the invention provides a self-crimping connector which is formed of a preformed sleeve having an aperture extending longitudinally of the sleeve. The sleeve is made of an electrically conductive material which possesses the property of being highly deformable radially outwardly of the aperture without failing in tension while maintaining a substantial degree of structural stability to retain the cohesive structure of the sleeve during and after deformation.

The invention further provides an electrical connection between an electrical conductor post and a conductor lead which is made by forcing the above self-crimping connector over the post and lead so that the post and lead are contained within the aperture of the connector. The conductor post is made of a material which is substantially hard relative to the connector while the lead is made of a material which is initially hard relative to the connector. Upon forcing the connector onto the post and lead, both of which are being held together, the lead begins to crush or penetrate into the connector radially and longitudinally of the aperture until the material of the connector about the deformed portion builds up sufficient resistance to equalize the crushing of the lead. Thereafter, the connector cooperates with the post to develop sufficient compressive forces on the lead to flatten the lead to a slight degree. The flattening of the lead and the crushing of the connector are sufficient to cause the material of the con-

nector and lead to fill and occupy the spaces which initially existed between the connector, post and wire at initial placement of the connector over the post and lead. After the connection has been forced down over the post and lead, the connector, post and lead are completely contiguous to each other so as to form an airtight or gastight connection.

In order to force the connector of the invention over a conductor post and a conductor lead, it is only necessary to develop a sufficient force longitudinally of the axis of the sleeve. Thus, any tool which is sized to the external dimensions of the sleeve can be used to force the connector into place within a limited working place.

These and other objects and advantages of the invention will become more apparent from the following detailed description and appended claims taken in conjunction with the accompanying drawings in which:

FIG. 1 illustrates a perspective view of a self-crimping connector of the invention;

FIG. 2 illustrates a view taken on line 2-2 of FIG. 1;

FIG. 3 illustrates a perspective view of a connection made between a conductor post and a conductor lead with the self-crimping connector of FIG. 1;

FIG. 4 illustrates a view taken on line 4-4 of FIG. 3;

FIG. 5 illustrates an exploded view of the connection of FIG. 4; and

FIG. 6 illustrates a step in the method of making the connector of FIG. 1.

Referring to FIGS. 1 and 2, the self-crimping connector 10 includes an outer circumferential shell 11 and an inner concentric sleeve 12 which is provided with an aperture 13 longitudinally of the sleeve 12. The shell 11 is formed of a material which possesses a high tensile strength relative to the material of the sleeve 12, for example, stainless steel, aluminum, fibrous-glass-reinforced plastics, etc. While the shell 11 is of a generally cylindrical shape so as to create an efficient tension member, any shape can be utilized, for example, a polygonal shape. The sleeve 12 is formed of a material which possesses a lower tensile strength than the shell 11. The material of the sleeve 12 also possesses a relatively high compressive strength and a structural property of being highly deformable without failing in tension while being sufficiently stable so as to substantially retain the structure of the sleeve during deformation. For example, the sleeve 12 is made of a sintered powdered metal.

Referring to FIGS. 3 and 4, the self-crimping connector 10 forms an electrical and mechanical connection between a conductor post 14 fixed to a support base 15 and a conductor lead 16, such as a wire. The post 14 and lead 16 are contained within the aperture 13 of the sleeve 12 of the connector 10 and completely fill the space within the connector 10. The connection is such that the lead 16 which, for example, is initially circular in cross section, becomes flattened between the sleeve 12 and post 14.

The conductor post 14 is made of an electrically conductive material which is harder than the wire 16 as well as harder than the sleeve 12 of the connector 10. The lead 16 is of an electrically conductive material which is initially harder than the sleeve 12 so as to penetrate into the sleeve but which becomes of equal strength to the penetrated portion of the sleeve 12 during penetration due to the compressive deformation of the penetrated portion of the sleeve so as to flatten between the sleeve 12 and post 14. The flattening of the lead 16 facilitates the complete filling of the aperture 13 of the sleeve 12 so that a gastight connection is formed.

Referring to FIG. 5, the connection between the post 14 which is circular in cross section and lead 16 is made by forcing the connector 10 concentrically over the post 14 and lead 16. For example, the lead 16 is initially placed above the post 14. This can be accomplished in a manner so that the post and lead are aligned in parallel relation or so that the lead 16 is at a slight angle relative to the post 14. Next, the connector 10 is positioned with the aperture aligned above the lead 16. The aperture 13 which is circular is of a diameter substantially

equal to the diameter of the post 14 so as to engage the post with a slide friction fit. Then, the connector 10 is brought down to envelop the lead 16 within the aperture 13. Subsequently, the connector 10 and enveloped lead 16 are both brought down onto the post 14. A force is then developed to further force or crimp the connector 10 down over the lead 16 and post 14 so that the lead 16 penetrates into the material of the sleeve 12. The penetration of the lead 16 proceeds until the material of the sleeve 12 in the area of the deformation becomes compressed to a degree sufficient to build up a reactive force equal to the strength of the lead. Thereafter, the sleeve 12 and lead 16 deform simultaneously so that the lead 16 flattens against the post 14 while the sleeve 12 deforms the flattened lead 16. The flattened lead 16 and rigid post 14 thus fill the aperture of the deformed sleeve 12 of the connector. After the connector 10 is forced down on the lead 16 and post 14 a sufficient distance to create a secure mechanical and electrical connection, the crimping force is removed.

The connection is such that the lead 16 is securely held within the connector between the sleeve 12 and post 14 so that a considerable force is necessary to pull the lead from the connection.

In order to facilitate the formation of a connection as described above, the mouth of the aperture 13 can be chamfered to initially envelop the post 14 and lead 16. Likewise, the top of the post 14 can be rounded as shown or tapered. In addition, the conductor post can be provided with an intermediate transverse bore for insertion of the end of the lead so as to hold the lead in place during crimping of a connector over the lead and post. The bore also serves to lock the lead in place after the connection has been made.

Referring to FIG. 6, in order to make a self-crimping connector 10, a shell 11 is initially placed in a die 17 concentrically of a mandrel 18 which is dimensioned to the size of the aperture 13 and fixed with respect to the die 17. A plurality of knockouts 19, 19' are positioned in the die 17 immediately below the shell 11 and mandrel 18, the knockouts being shaped to the dimensions of the mandrel 18 and the connector to be formed. With the shell 11 in place, a charge of powder particles, such as copper, nickel or other suitable metals or combination of metals, is deposited in the space between the shell 11 and mandrel 18. Next, a punch 20 which is shaped to slide on the mandrel 18 and which has a punch surface 21 with an external diameter slightly greater than the internal diameter of the shell 11, is brought down to compact the powder particles into a cohesive mass within the shell 11. The amount of compaction force generated on the powders is in the range of from 40,000 p.s.i. to 100,00 p.s.i. so as to compact the powder to a density within the range of from 60 percent to 85 percent of the density of a similar mass of solid metal. For example, where copper powder particles of a size of about -100 mesh are used for the charge, the compressive force is about 60,000 p.s.i. so as to compact the copper powder charge from a density of 2.8 grams per cc to 7.0 grams per cc. The compacted mass of powder particles forms a mass which has sufficient stability to be handled. After compaction, the punch 20 and mandrel 18 are removed, and the formed connector 10 is removed from the die 17 and knockouts 19, 19'.

Thereafter, the unit composed of the shell 11 and the compacted mass of powder particles is placed in a suitable furnace for sintering of the powder particles to form a unified sleeve 12 which is integrated with the shell 11. In order to sinter the compacted powder particles into the sleeve 12, the mass of particles is heated to a sintering temperature within the range of from 1,700° F. to 1,950° F. for a period of time between 20 minutes to 40 minutes and in a sintering atmosphere such as dry hydrogen or dissociated ammonia. For example, where copper powder particles of a size about -100 mesh are used,

the compacted mass is heated to 1,850° F. for 20 minutes in a sintering atmosphere of dry hydrogen.

It is to be noted that depending on the particle material used that the range of temperature and time may vary as well as the particular type of reducing atmosphere used. Accordingly, solely for purposes of brevity, the above ranges of temperature and time are given as guidelines and are not to be interpreted as exclusive for all suitable materials. The given ranges, however, are sufficient for materials such as copper, bronze, nickel, tungsten, nickel-tungsten mixtures, iron-nickel mixtures, and constantan.

During sintering the compacted mass of particles shrinks to a slight degree so as to make the sintered mass slightly more dense. For example, for the above charge of copper powder particles, the density increases to 8.0 grams per cc. Because of this shrinkage, the powder particles can be initially compacted by the punch 20 to slightly overfill the bore of the sleeve 12 in the die 17 so that after sintering a smooth even surface can be formed by the shell and sleeve.

After sintering, the integrated shell 11 and sleeve 12 which now constitute the connector 10 is then ready for use as described above.

Where sintered powder electrically conductive metal particles are utilized to form the connector of the invention, the sleeve formed by such materials should have a density in the range of from 70 percent to 90 percent of the density of an equivalent solid mass of the materials.

It is noted that the sleeve of the connector can be made of materials other than sintered powder particles. For example, the material can be a cast metal alloy which possesses the above described properties of deformability, strength and stability.

It is further noted that the connector of the invention can be made solely of a sleeve of material without a shell, provided the sleeve is of sufficient size to develop the strength of the conductor lead without failing in tension. In such a case, the outer peripheral portions of the sleeve have sufficient tensile strength to maintain the structural rigidity of the connector.

It is also noted that the connector can be of any suitable shape, such as polygonal, and that the aperture can be of any suitable shape sized to a conductor post and conductor lead, such, for example, as a square.

What I claim is:

1. An electrical connection comprising:
a conductor post;
a connector surrounding said post, said connector including
a radially deformable sleeve in contiguous relation to said
post;
a shell at the exterior of said sleeve, said shell being con-
tiguous to said sleeve and being of higher tensile strength
than said sleeve to maintain the unity of said sleeve during
radial deformation; and
a lead secured in flattened condition between said sleeve
and post, said sleeve closely conforming to said post and
said flattened lead.
2. An electrical connection as set forth in claim 1 wherein
said post is harder than said sleeve and said lead is initially
harder than said sleeve prior to flattening of said lead between
said post and sleeve.
3. An electrical connection as set forth in claim 1 wherein
said post and said lead completely fill the occupied space
within said connector to form a gastight connection.
4. An electrical connection as set forth in claim 1 wherein
said sleeve is of a material having the property of being
deformable radially outwardly thereof without failure in ten-
sion while maintaining a degree of stability to retain the struc-
ture of said sleeve.
